DESIGN FOR A COMBINATION PHOTO MOUNT AND COMPARTMENT OR ARTICLE OF SIMILAR NATURE

William W. Layton, Columbus, Ohio

Application July 18, 1945, Serial No. 120,789

Term of patent 7 years

(Cl. D61—1)

To all whom it may concern:

Be it known that I, William W. Layton, a citizen of the United States of America and a resident of Columbus, in the county of Franklin and State of Ohio, have invented a new, original, and ornamental Design for a Combination Photo Mount and Compartment or Article of Similar Nature, of which the following is the specification, reference being had to the accompanying drawing, forming a part thereof.

tion photo mount and compartment or article of similar nature showing my new design.

I claim:

The ornamental design for a combination photo mount and compartment or article of similar nature, substantially as shown.

WILLIAM W. LAYTON.
